SLINGSHOT PISTOL

Marvin Jarnagin, Detroit, Mich.

Application July 17, 1948, Serial No. 39,259

4 Claims. (Cl. 124—17)

1

This invention relates to missile projecting devices, and has particular reference to a slingshot with pistol like supporting and control means.

An object of the invention is to provide a slingshot which may be held, aimed and discharged in a pistol like manner.

Another object of the invention is to generally improve slingshots, and to provide a slingshot which is comparatively simple in construction, economical to manufacture, and efficient in use.

The foregoing and other objects and advantages of the invention will become more apparent as the description proceeds, reference being made from time to time to the accompanying drawings, forming part of the within disclosure, in which drawings:

Fig. 1 is a perspective view of the device embodying my invention and illustrating the relation of the parts when the device is in the cocked position.

Fig. 2 is a top plan view of the device illustrated in Fig. 1 after the missile has been projected.

Fig. 3 is a side elevational view of the device shown in Fig. 2.

Fig. 4 is a rear elevational view of the device shown in Fig. 3.

Fig. 5 is a section taken substantially on the line 5—5 of Fig. 3.

Referring now more particularly to the drawings, it will be understood that in the embodiment herein disclosed the reference character 7 indicates a supporting member which simulates the barrel of a pistol, to which is secured a hand grip 8. The members 7 and 8 are preferably mortised, as at 9, and are preferably secured together by means of a bolt 10, or other suitable means.

Stapled, as at 11, to the top of the supporting member 7, and extending longitudinally thereof and overhanging the ends is a pair of heavy wire members 12 and 13 which are preferably secured together along a predetermined area, as at 14. The free portions 15 and 16 are arranged to spring outwardly in diverging manner as shown in Fig. 2.

The forward ends of the members 12 and 13 are bent outwardly and upwardly to form supports 17 and 18 for elastic members 19 and 20. The rear ends of the members 12 and 13 are bent upwardly and outwardly to form fingers 21 and 22, which are arranged to hold the missile carrying element 23, in which is positioned a missile 24 to be projected. It will be noted that the missile 24 is positioned in the member 23 behind the fingers 21 and 22, so that the device remains in

2

cocked position so long as the fingers 21 and 22 are held closely together as hereinafter described.

Slidable in a slot 25 positioned in the hand grip 8 is a member 26 which consists of a pair of wires welded together along their front portion and bent downwardly to form a trigger 27. The wires comprising the member 26 extend upwardly in a diverging manner to define retainers 28 and 29 for the free ends of the members 12 and 13 as shown in Fig. 1. When the trigger 27 is depressed, the member 26 slides in the slot 25 moving the retainers 28 and 29 to the position as shown by the dotted lines in Fig. 1, in which position the free ends of the members 12 and 13, and the fingers 21 and 22 are permitted to spring outwardly to release the member 23, and the projectile 24. After the missile 24 is projected, the fingers 21 and 22 are pressed together whereupon the members 28 and 29 may be moved forwardly into the retaining position as shown in Fig. 1. Another projectile is then positioned in the member 23, and the elastic bands 19 and 20 are stretched rearwardly so that the new projectile positioned in the member 23 may be located back of the fingers 21 and 22. In this position the device is again ready to be discharged.

A slight bulge is formed, as at 30, on each of the members 12 and 13, which bulges serve to offer slight resistance to the rearward movement of the members 28 and 29 so that a safety factor is provided, whereby the device cannot be discharged without additional pressure being exerted on the trigger 27.

Having described my invention, what I claim and desire to secure by Letters Patent is:

1. In a device of the character described, the combination of a supporting member simulating the barrel of a pistol, a hand grip on said supporting member, a pair of rods supported in substantially parallel relation on said supporting element, said rods being bent and rebent to form posts for supporting elastic bands, elastic bands secured to said posts, the rear ends of said rods being bent to form fingers arranged to secure therebetween a missile carrying element secured to said rubber bands, and a slidable trigger having fingers arranged to secure therebetween the rear portions of said rods.

2. In a device of the character described in combination, a supporting member simulating the barrel of a gun, a hand grip secured to said supporting member, a pair of rods secured to said supporting member, said rods terminating at one end in a pair of posts adapted to accommodate

the ends of elastic bands, the other ends of said rods being bent to form a pair of springable fingers, and a trigger mechanism slideable in said hand grip, said trigger mechanism having means for holding and releasing said fingers for outward movement of said fingers with respect to the longitudinal median line of said supporting member.

3. In a device of the character described, the combination of a structure simulating a hand gun, a pair of rods secured to said structure, said rods being bent at the front end to form a U-shaped member adapted to support elastic bands, said rods being slightly divergent at the rear and being bent upwardly to form a pair of fingers for holding said elastic bands in stretched condition, and a trigger member slideable in said structure, said trigger member having a pair of fingers for holding the rear ends of said rods against divergence.

4. The combination defined in claim 3, in which there are protuberances formed near the rear end of said rods, said protuberances being arranged to co-act with the fingers of said trigger member to provide initial resistance to the releasing of said rods from the said trigger member.

MARVIN JARNAGIN.
